PORTABLE COMPRESSION TESTER FOR PLASTIC FOAM

Thomas R. Bishop, Hickory, N.C., assignor to Hickory
Springs Manufacturing Company, Hickory, N.C.

Filed Jan. 12, 1973, Ser. No. 322,912

Term of patent 14 years

Int. Cl. D10—05

U.S. Cl. D10—83

Fig. 1

Fig. 3

Fig. 2

Fig. 7

Fig. 5

Fig. 6

Fig. 4

FIG. 1 is a side perspective view of a portable compression tester for plastic foam showing my new design;

FIG. 2 is a side elevational view thereof;

FIG. 3 is an opposite side elevational view thereof;

FIG. 4 is a left end elevational view thereof;

FIG. 5 is a right end elevational view thereof;

FIG. 6 is a bottom plan view thereof;

FIG. 7 is a top plan view thereof.

I claim:

The ornamental design for a portable compression tester for plastic foam, as shown.
